UNITED STATES PATENT OFFICE.

GEORGE E. TYSON, OF READING, PENNSYLVANIA.

DESIGN FOR AN ESCUTCHEON.

SPECIFICATION forming part of Design No. 24,971, dated December 10, 1895.

Application filed October 24, 1895. Serial No. 566,790. Term of patent 7 years.

To all whom it may concern:

Be it known that I, GEORGE E. TYSON, a citizen of the United States, residing at Reading, county of Berks, State of Pennsylvania, have invented a certain Design for an Escutcheon, of which the following is a specification.

The main feature of my design is the representation of a grouping of leaves of conventional form focused about the converging border lines of the plate, as shown in the accompanying drawing.

Referring to the drawing, which illustrates my design as applied to a plain escutcheon-
5 plate, *a* represents a series of beads forming

the border or edge of the plate, and *b* the converging ends of said beads around which are grouped symmetrically at each end of the escutcheon leaves *c*, *d*, and *e* in various conventional forms and relative positions. 20

What I claim is—

The design for an escutcheon or similar article of builders' hardware, substantially as shown and described.

In testimony whereof I affix my signature 25 in presence of two witnesses.

GEO. E. TYSON.
